UNITED STATES PATENT OFFICE.

PAUL F. TAVEL, OF NASHVILLE, TENNESSEE.

COMBINED PAPER CARRIER AND GAUGE.

Application filed February 25, 1924. Serial No. 694,970.

To all whom it may concern:

Be it known that I, PAUL F. TAVEL, a resident of Nashville, in the county of Davidson and State of Tennessee, a citizen of the 5 United States, have invented certain new and useful Improvements in Combined Paper Carriers and Gauges, of which the following is a specification.

My invention relates to improvements in 10 combined paper carrier and gauge, which is particularly designed and adapted for use in conjunction or connection with a punching machine, but which may be employed for any purpose where it would operate in an 15 efficient and practical manner.

One object of my invention is the provision of a mechanism which will carry the paper or other material and which will present it to the action of the punch or other 20 structure in an absolutely accurate position to insure the highest degree of efficiency.

Another object of my invention is the provision of a mechanism which will be manually controlled by a single attendant and 25 which will perform its functions in a rapid and reliable manner and prove a great saving of time, labor and money.

Another object of my invention is the provision of a machine which will convey any 30 desired amount of paper to the punch or other device, which can be adjusted to the finest degree, which can be easily operated and controlled by a single attendant, and which will be simple, strong and durable 35 and inexpensive to manufacture, thus possessing all requisites to produce a practical and efficient mechanism.

With these objects in view my invention 40 consists of a paper carrier and gauge embodying novel features of construction and combination of parts, substantially as described and claimed and as shown in the accompanying drawings, in which:

Figure 1 represents a top plan view of a 45 combined paper carrier and gauge constructed in accordance with and embodying my invention.

Figure 2 represents an edge view of the paper carrier element of my machine.

Figure 3 represents a detail view of the mechanism for retaining the carrier or carriage in the proper adjustment.

Figure 4 represents an end view of the complete machine, and

Figures 5 and 6 represent detail sectional

views on an enlarged scale to show important details of my invention.

In the drawings the same numerals are used to indicate the same parts in all the views. The numeral 1 is a suitable table or 60 bed, which is of the proper and desired size and is supported on suitable legs 2, and for purpose of illustration a punch 3, mounted in a guide, and operated by a cam or eccentric 4, on a shaft 5, is shown.

It will be understood that no claim for a punch is made herein and that my machine can be adapted for use in connection with a punch, or in fact with any other means where it would serve its function.

Upon the table is secured the base element or plate 6, which is of elongated or oblong shape and of the desired size, having at one side the pair of arms 7, which are slotted at 8, and have mounted therein the adjusting 75 threaded rods 9, which travel in the studs or posts 10, and have mounted on their inner extended ends the vertically disposed bevel gears 11, which mesh with the similar horizontally disposed bevel gears 12, to which 80 are connected the hand operated cranks 13, the rotation of which effects rotation of the threaded rods and naturally moves the base element or plate in or out for adjusting the same to the finest possible degree.

From this construction it will be apparent that the base plate is capable of instant manual adjustment and upon said plate is mounted the rail 14, provided at determined points with stops 15, said stops being removable if desired to change their position on the said rail, and parallel with said rail 14, is a rail 16, having a series of sleeves 17, receiving the spring-actuated detents 19, which engage the stops 15, to retain the paper carrier 20 at the desired adjustment with reference to the punch or other co-operating mechanism.

The paper carrier is of open box like shape and is provided with the pair of rollers 21, which travel within the rail 16, and is also provided with the end roller 22, which moves over the base plate, while at one end the carrier has a stop plate 23, which is connected to hand operated adjusting screws 24, which adjust the stop plate to insure the paper or other material being in the exact position to insure the proper presentation to the punch, whose relation is shown in dotted lines in Figure 1.

Upon the flange 25, at the inner edge of the carrier is mounted the hand grasp 26, which is pivoted at 27, to the inner ends of the pair of levers 28, fulcrumed at 29, to the 5 flange of the carrier and having their outer ends connected to the actuated detents 19, thus by pressure of the hand on the grasping portion releases the detents 19, and permits the attendant to move the carrier to the 10 desired adjustment or to cause it to engage the desired stop 15, a suitable guard 30 being disposed in proper relation to the detents and operating levers therefor.

The operation of my machine will be 15 readily understood from the drawings taken in connection with the description and I would state that the paper to be punched or operated upon is placed in the carrier and adjusted with relation to the punch and then 20 the carrier is adjusted longitudinally by means of the manually operated and controlled spring actuated detents and is adjusted transversely by manual operation and control of the base plate and the punch 25 can then be put in action and its work will be absolutely reliable, rapid and accurate by means of my carrier and gauge.

The machine is particularly useful in connection with a punching machine where the 30 paper is to be punched with openings in accurate arrangement, but the structure may be adapted for other service and perform its functions in a practical manner and further the machine is susceptible of many 35 slight changes and modifications which fall within the scope of my claims.

It will be noted that the rail 16 is either made of two parallel sections or it may be slotted to receive the grooved rollers and 40 also allow the movement of the detent carrying means back and forth within the space or slot, as clearly shown.

I claim:

1. In a combined paper carrier and gauge, 45 the combination of a table or support, a base plate adjustable transversely on said support and a carrier mounted on said base plate and adapted to travel in the base plate and upon the table, said carrier moving and 50 adjustable longitudinally in said base plate.

2. In a combined paper carrier and gauge, the combination with a table or support, a 55 base plate adjustable transversely thereon, a guide connected to and movable with said base plate, manually operated adjusting screws for adjusting the base plate on the support, a series of stops carried by said bed plate, a paper carrier mounted in said bed plate and movable longitudinally with 60 reference to said stops, and manually operated and controlled devices mounted on the said carrier to engage said stops to adjust and retain the carrier.

3. In a combined paper carrier and gauge, 65 the combination with a table or support, a

base plate adjustably mounted thereon, a series of longitudinally arranged stops carried by said base plate, a guide rail on said base plate parallel with said stops, a paper carrier adapted to travel longitudinally on 70 the base plate and upon said guide rail, paper adjusting means connected to said paper carrier, and manually controlled and operated detents mounted on the carrier and engaging said stops to secure the carrier in 75 longitudinal adjustment.

4. A combined paper carrier and gauge, consisting of a support, a base plate mounted thereon for transverse adjustment, a carrier mounted in and movable in said base plate 80 for longitudinal adjustment, and manually operated and controlled means for effecting said transverse and longitudinal adjustments, said means consisting of hand controlled detents on the carrier engaging the 85 bed plate to secure longitudinal adjustment of the carrier, and hand operated screws mounted in the base plate and engaging the support to obtain transverse adjustment of said base plate. 90

5. A combined paper carrier and gauge consisting of a stationary support, a base plate mounted on said support and having a transverse adjustment thereon, a rail carried by said support, and having a slot, a carrier mounted on said support, and connected to the slot of said rail of the base plate to move longitudinally therein. 95

6. A combined paper carrier and gauge consisting of a stationary support, a base 100 plate carrying a slotted rail and adjustable transversely on said support, a carrier movable longitudinally on said support and rollers carried by said carrier and traveling in said slotted rail. 105

7. A combined paper carrier and gauge consisting of a rigid support, a base plate mounted and adjustable on said support, a guide rail carried by said base plate and formed with a slot, a rail disposed parallel 110 with said guide rail; stops carried by said rail, a carrier mounted on said support and adapted to travel longitudinally in the slot of said guide rail, and manually operated and controlled means carried by said carrier 115 for engaging said stops to secure the carrier in the desired longitudinal adjustment.

8. In a gauge for punching machines, the combination of a table, studs rising therefrom, a base plate resting flat on said table and having slotted arms adapted to be guided on said studs, manually operated screws engaging the studs and base plate to adjust said base plate transversely, a paper carrier connected with and movable longitudinally with reference to the base plate, and means for retaining the carrier in the desired longitudinal adjustment. 120

9. In a gauge for punching machines, the combination of a table, studs rising there- 125

from, a base plate resting on said table and having slotted arms guided on said studs, screw mechanism connected with the base plate, and studs for adjusting the base plate
5 transversely, a slotted guide rail carried by said base plate, a rail arranged parallel with said guide rail, a series of stops carried by said rail, a work carrier mounted on wheels guided in said slotted rail and spring de-
tents carried by said work carrier and en-
gaging said stops to retain the carrier in the
desired longitudinal adjustment.

In testimony whereof I hereunto affix my signature.

PAUL F. TAVEL.
